METHOD OF BONDING THE ENDS OF WIRE ROPES

Frank E. Stahl, Tonawanda, N. Y., assignor to
Columbus McKinnon Chain Corporation, Tonawanda, N. Y., a corporation of New York

Application March 17, 1936, Serial No. 69,341

6 Claims. (Cl. 29—148)

My invention relates in general to the bonding of the wires and strands at the end of wire ropes, and in particular to the cutting of the rope into lengths and the subsequent welding of the wires and strands thereof at the ends of such lengths.

Reference is to be had to application Serial No. 69,342, upon Apparatus for bonding the ends of wire ropes which contains subject matter common to this application.

10 It is well known to those skilled in the art that in all wire rope except that which is initially preformed, the wires and strands will fly apart and become unraveled when the rope is cut through, thus making it necessary, when cutting or splicing such rope, to provide a number of seizures.

Furthermore, when the rope is to have an anchor attached to the extreme outer end thereof, such seizures obviously cannot be used, because they must be located as near the outer end as possible. Moreover, when such an anchor is to be used, it is important that the end of the rope be maintained at its initial diameter.

The principal object of my invention has been to create a method whereby a wire rope may be held and cut to the desired length without having to provide and to apply seizures to the ends of the rope.

Another object has been to provide a method whereby the individual wires and strands at the 30 end of the rope may be securely bonded together without the use of seizures so that they will not fly apart or become unraveled.

Another object is to provide a method of welding the wires together at the end of the rope 35 and to provide a cover thereat.

My method accomplishes the above results and advantages and may be carried out by any suitable form of apparatus, one form of which is 40 shown in the accompanying drawings. In the drawings, where I show the wire rope broken off it is to be understood that the broken off part is either connected to the reel of wire rope (not shown) or to the severed length, the other end 45 of which has been previously bonded.

In the drawings:

Fig. 1 is a fragmentary, perspective view showing a wire rope having its severed end bonded in accordance with my method.

50 Fig. 2 is a front elevation of an apparatus for carrying out my method.

Fig. 3 is a plan view thereof.

Fig. 4 is a fragmentary, side elevation of the device, showing a transverse, sectional view taken 55 on line 4—4 of Fig. 2.

Fig. 5 is a fragmentary, transverse, sectional view taken on line 5—5 of Fig. 2.

Fig. 6 is a similar view taken on line 6—6 of Fig. 2.

Fig. 7 is a plan view of the apparatus showing 5 a wire rope which has been severed in accordance with my method.

Fig. 8 is a front elevation showing the apparatus in a position to have the ends of the wire rope welded.

10 In Fig. 1, I show the end 10 of a length 19 of wire rope 18 which has been severed and bonded in accordance with the steps of my invention. As here shown, the ends of the wires and strands have been welded together and a cover 11 has 15 been welded over the top, thus providing not only a bond for the strands and wires, but closing the end of the rope, sealing in the hemp cord, if the rope is so provided, and providing an end which is stiff and rigid and one which cannot unravel.

20 In carrying out my invention by the apparatus shown in Figs. 2 to 8, inclusive, I use a bench vise 12 having a front movable jaw 13 and a rear stationary jaw 14. The movable jaw is operated by means of the vise screw 15.

25 Arranged between the jaws 13 and 14 of the vise are two clamping blocks 16 and two clamping blocks 17 arranged in pairs. The blocks 16 are arranged at that side of the vise which receives the wire rope 18 as it comes from the reel (not shown), and the blocks 17 are arranged at the opposite side of the vise jaw for the purpose of clamping that portion of the rope which is to become the severed length 19. The blocks are so proportioned and positioned that a space 20 is 30 provided between them for the accommodation of any suitable mechanical cutting tool, or an oxy-acetylene flame. One of the blocks 16 is pivotally connected to the coacting jaw 13 by means of a pivot pin 26, and the other block is 35 likewise pivotally connected to its coacting jaw 14 by means of a similar pivot pin 26. (Fig. 6.) Each of these pivot pins is arranged preferably near the bottom of the block and in the central portion thereof, and each is preferably driven into 40 a suitable aperture formed in the block. The pins have their ends protruding beyond the outer surfaces of the blocks and are pivotally disposed in apertures 21 formed in the jaws of the vise. Each of the blocks 16 and 17 is provided in its 45 inner working face with a semi-cylindrical groove 33 for the accommodation and clamping of the wire rope. The blocks 16 are loosely connected together by means of a bolt 28, and the blocks 17 are likewise loosely connected together 50

55

by means of a similar bolt 28. Each of these bolts passes through an aperture 29 in one of the blocks of each pair and into a screwthreaded aperture 30 in the opposite block of the same pair. The head 31 of each of the bolts is disposed in a countersunk aperture 32, the depth of the aperture being so proportioned in relation to the position of the head 31 of the bolt that the blocks of each pair can open slightly so as to permit the free passage of the wire rope therebetween, but cannot be separated from each other far enough to allow the rope to become disengaged from the grooves 33 and thereby fall out from between the blocks. The adjacent surfaces 21 of the blocks of each pair are so proportioned that there is sufficient clearance between them when the rope is clamped.

It is desirable to provide means for positively separating the blocks 17 for the reason that the next length to be severed must enter between them. This is not necessary with the blocks 16, since the rope coming from the reel is always threaded therebetween. In order to accomplish this, one of the blocks 17 is pivotally attached 25 to the vise jaw 13 by means of a screw 36, and the other block 17 is likewise pivotally attached to the jaw 14 thereof by means of a similar screw 36. Each of the screws 36 is slidably and rotatably mounted in an aperture 37 formed in 30 each of the blocks 17 and screw threaded to its respective vise jaw. The head 38 of each of these screws is disposed in a countersunk aperture 39 formed in each of the blocks, the depth of which aperture is so proportioned in relation to the length of the screw 36 that there is some space 35 between the bottom of the aperture and the bottom surface of the head of the screw, which will permit some slight lost motion between each of the blocks and its coacting vise jaws. By this arrangement, the blocks 17 will not only be pivotally mounted but they may be positively separated from each other by the actuation of the vise jaw 13 after the heads 38 have reached the bottoms of the countersunk apertures 39. Such engagement will, furthermore, prevent opening of the vise jaws an undesirable amount, since the screw 28 will limit the opening of the blocks 17. By this construction the end of the rope which is being loosely held by the block 16 may easily enter 40 between the blocks 17 when another length of rope is to be severed and bonded.

A stop pin 41 is provided for the blocks 16 and a similar pin 41 is provided for the blocks 17. Each of these pins passes through both of the blocks of each pair and extends a slight distance beyond the outer faces of each block, so as to contact with the upper surfaces of the vise jaws 13 and 14 and thereby act as stops to limit the inward rotation of the blocks upon their pivots, 55 as shown in Figs. 2, 4, and 5.

In carrying out my invention by the use of the apparatus herein shown and described, the vise jaws are opened and the wire rope 18 is threaded through the blocks 16 and also through the blocks 17, the rope coming from the reel (not shown) being moved during such threading operation in the direction of the arrows shown in Figs. 2 and 3. The rope is extended on through the blocks until the place where it is desired to 65 sever the rope is located in the space 20 between the pairs of clamping blocks, a trough and stop (not shown) being provided, if desired, for the reception and support of the wire rope as well as for the gauging of its length thereof. After 70 the rope has been drawn through the blocks 75

16 and 17 the predetermined length, the screw 15 of the vise 12 is used to move the jaw 13 toward the jaw 14 and to thus firmly clamp the wire rope between the coacting blocks 16 and the coacting blocks 17. As hereinbefore stated, 5 the pairs of blocks 16 and 17 are separated so as to provide a space 20 therebetween in which the rope may be severed by any suitable means. A saw, either hand or power operated, may be used to sever the rope, and in some cases it may 10 be necessary, when a saw is used, to provide a slot (not shown) in the vise jaws for the reception thereof. I have found, however, that an oxy-acetylene flame is a very convenient means of severing the rope, not only because it is a most suitable medium for cutting but also because of the fact that such a flame can also be used for welding the strands and wires of the rope together at the rope ends and in the formation of the covers 11. While any suitable means may 15 be employed to sever the rope, it must be of such nature that the initial diameter of the rope will be substantially maintained. After the wire rope has been clamped by the two interspaced pairs of blocks, as shown in Figs. 2 and 3, it is ready 20 to be severed in the formation of the length 19. When the rope is severed by an oxy-acetylene flame, gobs 42 of solidified metal will usually be formed on the severed ends of the rope, as 25 shown in Fig. 7.

After the wire rope has been severed, as shown in Fig. 7, the screw 15 of the vise 12 is loosened slightly and the workman then grasps the portions of the rope extending outwardly from each of the pairs of blocks 16 and 17, and by bearing 30 down upon these portions causes the pairs of blocks 16 and 17 to be rotated, the blocks 16 rotating about the pivot pins 26, and the blocks 17 rotating about the pivot screws 36. The blocks are rotated through substantially 90°, which will 35 bring the ends of the two portions of the rope above the upper edge of the jaws 13 and 14 of the vise, as shown in Fig. 8. These severed 40 ends will also project slightly beyond the pairs of blocks 16 and 17, in the position shown in 45 Fig. 8. The workman now, by the use of the oxy-acetylene flame, will burn off the gobs 42 from each of the rope ends, thus making a substantially even end. The workman will then also, 50 by the use of this flame, weld together the wires and strands of the upturned ends and will also deposit metal upon such ends, thereby forming the covers 11, shown in Figs. 1 and 8. In such welding and in the formation of the cover, the wires and strands of the rope are welded together 55 so as to make the extreme end of the rope one single integral piece, so that when the welded rope is released from the clamping action of the pairs of blocks 16 and 17, the wires and strands cannot become unraveled or fly apart.

It is to be understood that after the rope has been severed and before the ends thereof are welded, the jaws of the vise are loosened just sufficiently to permit the operator to rotate the pairs of blocks 16 and 17 about their pivots, but not enough to release the clamping action of the pairs of blocks upon the wire rope to such a degree as to permit the rope to become unraveled.

After the severed ends of rope have been welded, as above described, the vise jaws are 70 released and the pairs of clamping blocks are again rotated on their pivots in reverse direction so as to bring them to their initial positions where the stop pins 41 will contact with the tops of the vise jaws. The length of rope 19 (covered 75

at each end) is now removed from between the blocks 17. If the jaws have not been sufficiently released so as to permit the free passage of the rope between the blocks, the jaw 13 is further 5 opened. As this jaw is opened, it will separate the blocks 17 because of their attachment to the jaws by the pivot screws 36, and thus permit the free passage of the rope therebetween. The wire rope 18 coming from the reel (not shown), with 10 its end covered, is now moved along engaged between the blocks 16 and between the semi-cylindrical recesses of the blocks 17. The rope is continued on until the end engages with the stop (not shown) for the gauging of the next 15 length 19, whereupon the vise jaw 13 is again clamped in position, thus securely holding the rope between the jaws 16 and 17 ready to be severed at the place in the space 20 between the pairs of blocks, as hereinbefore described.

20 Having thus described my invention, what I claim is:

1. A method of bonding the ends of wire ropes, comprising the clamping of the rope between pivotally mounted blocks on each side of the 25 portion to be severed, severing the rope by means of an oxyacetylene flame, then rotating the blocks so as to position the severed ends for convenient welding while firmly holding them in said blocks, and then welding together the wires 30 and strands of the rope at the severed ends independently of the step of severing the rope.

2. A method of bonding the ends of wire rope, comprising clamping spaced-apart portions of the rope on each side of and closely adjacent to the place where it is to be severed, then severing the rope between the clamped portions while substantially maintaining its initial diameter, then moving the portions at the severed ends out of axial coincidence and into positions for 35 convenient welding, while maintaining the clamping action upon such portions, and then subsequently welding together the wires and strands of each of the severed ends by steps performed subsequently to the cutting of the rope.

45 3. A method of bonding the ends of wire rope, comprising clamping spaced-apart portions of the rope on each side of and closely adjacent to the place where it is to be severed, applying an oxyacetylene flame to the rope between the 50 clamped portions, thereby severing the rope, then moving the portions at the severed ends out of axial coincidence and into positions for convenient welding, while maintaining the clamping

action upon such portions, and then subsequently applying said flame to each of the severed ends of the rope, thereby welding together the strands on each of such severed ends.

4. A method of bonding the ends of wire rope, 5 comprising clamping spaced-apart portions of the rope on each side of and closely adjacent to the place where it is to be severed, applying an oxyacetylene flame to the rope between the clamped portions, thereby severing the rope, then 10 moving the portions at the severed ends out of axial coincidence and into positions for convenient welding, while maintaining the clamping action upon such portions, then again applying said flame to the ragged ends of the wires at 15 the severed surfaces of the rope ends, thereby smoothing the ends, and then subsequently applying said flame to each of said severed ends of the rope, thereby welding together the strands on each of such severed ends, by steps performed 20 subsequently to the cutting of the rope.

5. A method of bonding the ends of wire rope, 25 comprising clamping spaced-apart portions of the rope on each side of and closely adjacent to the place where it is to be severed, then severing the rope between the clamped portions while substantially maintaining its initial diameter, then moving the portions at the severed ends out of axial coincidence and into positions for 30 convenient welding, while maintaining the clamping action upon such portions, then subsequently welding the ends of the wires together at each end of the rope by steps performed subsequently to the cutting of the rope, and simultaneously therewith, covering each of the 35 severed ends by depositing weld metal thereon.

6. A method of bonding the ends of wire rope, 40 comprising clamping spaced-apart portions of the rope on each side of and closely adjacent to the place where it is to be severed, then severing the rope between the clamped portions while substantially maintaining its initial diameter, then moving the portions at the severed ends out of axial coincidence and into positions for 45 convenient welding, while maintaining the clamping action upon such portions, then smoothing off the ragged ends of the wires on the severed surfaces at the rope ends, then subsequently welding the ends of the wires together by steps performed subsequently to the cutting of the rope, and simultaneously therewith covering each of said severed 50 ends by depositing weld metal thereon.

FRANK E. STAHL.
